My

UNITED STATES PATENT OFFICE.

DOMINGO DESPLATS, OF BUENOS AYRES, ARGENTINA.

DOOR-CHECK.

942,622.

Specification of Letters Patent.

Patented Dec. 7, 1909.

Application filed February 23, 1909. Serial No. 479,454.

To all whom it may concern:

Be it known that I, DOMINGO DESPLATS, shorthand typist, a citizen of Argentina, and residing at 240-25 de Mayo street, Buenos Ayres, Argentina, have invented an Improvement in Door-Checks, of which the following is a specification.

This invention relates to that class of door checks which are provided to prevent the door or window from coming into contact with the wall and also to catch automatically and maintain it in open position against any ordinary wind or other cause to prevent slamming.

The objects of this invention therefore are to provide an automatic catching device and a means for automatically releasing the door at will without the necessity of stooping to release the catch. These objects are attained by means of the device illustrated in the drawing in which—

Figure 1 is a side elevation of the device secured in place. Fig. 2 is a plan view thereof. Fig. 3 is a sectional view on line 3—3 of Fig. 1.

In the construction the member A is attached to the floor or wall and carries a circular toothed element or ratchet wheel B secured to said member A by means of a stud D and washer C. A counter support E is attached to the door or window and supports in a horizontal position the catch plate G, which has a slot P' to engage with the teeth in the ratchet wheel B.

The counter support E in its preferred form consists of a plate adapted to be bent

in the shape of a trough, with its open side toward the door, said plate being provided with a hole M for the fastening screw, and with a recess E adapted to hold the catch G. The catch plate G has lateral recesses L and a downward rear extension by means of which it is suspended on the support E in order to maintain it in a horizontal position as shown in Fig. 1.

The washer C and stud screw D attach the ratchet wheel to the support A in a manner which prevents the free movement of the wheel. The ratchet plate G, when the door is opened, moves over the teeth N of the wheel B and catches; the friction of the washer C and stud screw D holds the door in an open position against the wall under nearly all ordinary conditions, but a more than usual pressure against the door causes the ratchet wheel to turn sufficiently to release the catch, and door.

I claim—

A door check comprising in combination, a fixed member, a circular toothed element, means frictionally securing said element to said member to retard rotation of the former, and a device mounted upon the door and provided with a portion for automatic engagement with and disengagement from said toothed element.

In testimony whereof I affix my signature in presence of two witnesses.

DOMINGO DESPLATS.
